UNITED STATES PATENT OFFICE

EDWIN H. MANVELL, OF BROOKLYN, NEW YORK, ASSIGNOR TO EDWIN H. MANVELL AND LOUIS CASPER, BOTH OF BROOKLYN, NEW YORK

TAPE MOISTENING AND AFFIXING DEVICE

Application filed April 23, 1929; Serial No. 357,374.

My invention relates to improvements in the art of moistening and affixing gummed paper tape upon paper, cardboard or similar substances and particularly for use in connection with moistening and affixing gummed paper tape operating in connection with telegraph printers.

The object of my invention is to provide a simple and effective hand operated device whereby paper tapes that have been previously gummed may be moistened and affixed upon paper blanks or the like; and this is accomplished without recourse to felt or other wicks and requiring a minimum of maintenance which is not the case with moisteners of this class that employ wicks or felts as a moistening medium.

As a further description of my invention, attention is directed to the accompanying drawing forming a part of this specification and in which

Fig. 1 is a sectional view of the moistening and affixing device with the paper tape fed through the same on a line 1—1 of Fig. 2.

Fig. 2 is a top plan view of the device.

Fig. 3 is a detail of the head 2 on a line 3—3.

In all of the foregoing views corresponding parts are represented by the same numerals of reference.

1 is a semi-translucent receptacle for holding water or other liquids. This receptacle is also used as a handle.

Attached to the liquid holding receptacle 1, 35 is, as a whole, a head 2 which is screwed on to the receptacle 1. Between the threads of the head 2 and the liquid holding receptacle 1 is a rubber gasket 22 which is used to prevent leakage of water or other liquid through the aforementioned threads, thus making the device water tight in so far as the connection between the head 2 and receptacle 1 is concerned.

Mounted loosely above the receptacle 1 is 45 a tape holder 18 through an opening of which the paper tape is threaded. Secured to the sides of the tape holder are two flexible clips 19 which secures the tape holder 18 on to the periphery of the receptacle and also permits 50 its ready removal when desired. Secured to

the end of the tape holder toward the head 2 is a combination tape lifter and holder 7. 5 is a shaft bearing between lugs 8 and upon which the tape lifter 7 swings. The tape lifter is held in resilient tension upon the 55 paper tape 10 resting in the groove 21 by means of the curved shoe 15 which is attached to the curved support 4 which in turn is integral to the tape lifter 7. 6 is a coiled spring which maintains a downward pressure on the 60 tape lifter 7. 16 is a pin projection over which the paper tape is threaded. 20 is a thumb piece continuation of the tape lifter 7, which when pressed upon downwardly causes the tape lifter to rise as shown in dotted 65 lines and taking the paper tape with it lifting it clear of the moistening or gumming roller 3.

This is employed when the device is not in use and prevents the paper tape from adhering to the roller 3 during its inactive period.

The moistening or gumming roller 3 is revoluble in the well 17. The walls of the well are conformed to the shape of the roller as shown in Fig. 1. This enables the roller to 75 readily take up any liquid that may flow into the bottom of the well. The roller 3 revolves on a shaft 9, the latter being removable thereby permitting the roller 3 to be lifted out of the well when desired for examination, maintenance, or renewal. The shaft 9 is substantially secured by means of a spring arrangement 23 shown in detail in Fig. 3. The shaft 9 being slotted near the end of the same and projects outward from the head 2. The wire 80 springs at 23 readily fit themselves into said slot holding the shaft substantially in its normal position until it is pulled out at the opposite side when it is desired to remove the roller 85 3 as described.

The well 17 receives a water or other liquid supply from the combined reservoir and receptacle through orifices 11 and 11'. The diameter of the latter determines in a large 90 measure the extent of the liquid flow into the well 17. Therefore, in order to provide the proper liquid flow on the periphery of the roller 3, it is desirable to have the size of the orifices 11 and 11' determined to a nicety.

The level of liquid in the well 17 is pri- 100

marily governed by the revoluble movement of the gumming or moistener roller 3. This is because of the following action: The wa-
5 ter or other liquid first starts to flow through orifice 11' and continues to flow until the level of the liquid in the well has risen above the orifice 11. This prevents the air from flowing through the orifice 11, and, as a consequence the flow of water or other liquid
10 through the orifice 11' ceases.

When the roller 3 is revolved by means hereinafter explained, it picks up water or other liquid on its periphery from the bottom of the well 17. The liquid thus ob-
15 tained goes to moisten the under portion, usually the gummed portion of the paper tape 10 passing over the top periphery of roller 3. This results in a fall of the liquid level in the well 17. When the liquid level
20 shall have been so reduced that the orifice 11 is exposed, the water or other liquid will immediately start flowing into the well 17 through the orifice 11' and will continue to flow until the upper orifice 11 is again cov-
25 ered resulting in a cessation of the flow of liquid through the orifice 11' for the reason already stated. The faster the roller 3 re-
volves, the faster will the flow of liquid continue through the orifice 11', or contrary
30 wise, if the roller movement is slower the liquid feed into the well 17 will likewise be slower. This is as it should be, the faster the tape 10 is drawn over the periphery of the roller 3, the greater will there be need
35 of liquid supply to the under portion of the tape 10, and conversely, if the movement of the roller is slower, less liquid will be required.

Another advantage that I have discovered
40 in the foregoing combination is that as the liquid becomes impregnated with the residue gum from the paper tape, the moistening or gumming action becomes more efficient. Assuming this to be the case, it is obvious that
45 the maintenance of such a device is practically nil.

The paper tape 10 passes over the roller 3 which is made of bakelite or similar insu-
50 lated semi-porous material and then over a pair of guide wires 13, under a fixed roller 14 at the nose 12 of the head 2 and then passes outward. The paper tape after it has been drawn out of the moistening and affixing device is properly moistened or gummed
55 ready to be affixed on to a paper blank or other similar surface by the operator holding said moistening and affixing device.

The operation of the device is as follows: The paper that is to be moistened or gummed
60 and affixed is threaded through the tape holder 18, then the tape lifter 7 is lifted slightly and the paper is passed into groove 21 under shoe 15 but over the projecting pin 16, then over the moistening or gumming roller 3, then under the fixed roller 14.

The device is held horizontally in the right hand and the tape is drawn out with the left hand. A portion of the tape is then gummed on to the paper blank in the case of tape coming from a telegraph printer. The tape is further drawn out and gummed to a paper blank or other surface and is cut into proper lengths at the end of a line as in the case of a telegraph message, or in shorter lengths to conform to the form of the message. The cutting of the paper tape is accomplished by a special paper cutter attached like a thimble to the index finger of the left hand.

The device is also applicable for sealing packages with paper tape coming through the device from a paper roll mounted on a stand where it is free to unroll.

It will be noticed in Fig. 2 that the head 2 of the device is at an angle with the liquid holding receptacle.

The angle is made to conform with the natural angle of the hand so that the tape feed from the device is perfectly straight although the device is held in a more or less angular manner. This arrangement makes it more restful for the operator in preference to a head being perfectly straight with relation to the liquid holding receptacle when the latter is held in the hand.

It can be readily seen that my invention is capable of considerable modification without departing from the spirit or essential features of my invention. For instance, the device can be arranged to be held vertically instead of horizontally and the head arrangement made to conform to such position. While I have found bakelite or equivalent semi-porous insulated material the best composition for the moistening wheel 3, other materials may be used such as aluminum, brass, wood, and so forth.

Now having described my invention, what I claim as new is:

1. In a tape moistening and affixing device having a head attached to a liquid holding receptacle, a well incorporated in said head, a moistening or gumming wheel revoluble in said well, means for feeding liquid from said holding receptacle into said well, said means coacting with the movement of said wheel, a tape groove, a spring pressed curved pressure shoe resting normally upon the gummed paper tape that rests in said groove preparatory to being moistened; a tape guide embracing the tape and integral with the lower face of said shoe, and a finger lever integral with said shoe for lifting the tape clear of the gumming or moistening wheel aforesaid.

2. In a tape moistening and affixing device having a head attached to a liquid holding receptacle, said head having tape guiding means and means for moistening or gumming paper tape passing through the same, and said head and tape guiding means having an

angular inclination laterally with respect to the liquid holding receptacle to which said head is attached.

3. In a tape moistener or the like, a body providing a reservoir and an adjacent well whose bottom ends are formed in the arc of a circle, there being a fluid supply duct and a superjacent vent duct communicating from said well to the reservoir, both ducts being 10 below the level of the fluid in the reservoir, a freely revoluble moistening roller in said well and providing an anti-friction tape support, said roller having its sides and periphery closely spaced to the opposed walls of the 15 well whereby to prevent rise of the fluid level in the well above said vent duct.

4. In a tape moistener or the like, a body providing a reservoir and an adjacent well having an arcuate bottom, a fluid supply duct 20 and a superjacent vent duct communicating from said reservoir to said well, means for preventing the rise of fluid in said well above the level of said vent duct and comprising a freely revoluble tape supporting roller 25 having its periphery and sides closely spaced to the bottom and sides of the well, and said supply duct discharging through the curved bottom of the well against the periphery of said roll.

30 5. In a tape moistener or the like, a body providing a reservoir and an adjacent well having an arcuate bottom, a fluid supply duct and a superjacent vent duct communicating from said reservoir through the bottom of 35 said well, means for preventing the rise of fluid in said well above the level of said vent duct and comprising a freely revoluble tape supporting roller having its periphery and sides closely spaced to the bottom and sides 40 of the well, said fluid from said supply duct discharging against the periphery of said roller whereby the same when in motion will accelerate the flow.

EDWIN H. MANVELL.
